UNITED STATES PATENT OFFICE.

EDWARD HENRY SHORTMAN, OF BLOXWICH, ENGLAND, ASSIGNOR OF ONE-HALF TO THE NEW DELAVILLE SPELTER COMPANY LIMITED, OF SPRING HILL, BIRMINGHAM, ENGLAND.

APPARATUS FOR EXTRACTING ZINC.

No. 907,416.

Specification of Letters Patent.

Patented Dec. 22, 1908.

Original application filed December 13, 1907, Serial No. 406,391. Divided and this application filed September 17, 1908. Serial No. 453,482.

To all whom it may concern:

Be it known that I, EDWARD HENRY SHORTMAN, a subject of the King of Great Britain, residing at Bloxwich, in the county 5 of Stafford, England, have invented certain new and useful Improvements in Apparatus for Extracting Zinc, of which the following is a specification.

This invention has reference to an apparatus adapted for use in extracting zinc, wherein provision must be made for the interception and condensation of any vaporized lead that may have been carried over with the zinc vapors from the furnace retorts, 15 such interception of the lead being effected prior to the condensation of the purified zinc in the receivers or condensers.

In one form of apparatus heretofore used for eliminating the lead prior to the condensation of the zinc, a lead-intercepting and filtering medium consisting of pieces of refractory material, (such as broken fire-brick), has been arranged between the vaporizing area and the condensing area, such medium 25 being usually arranged in the inner or retort end of the receiver in such a manner that the whole of the vapors from the retort have to pass through and be subjected to the action of the medium which retards the flow of the vaporized metals sufficiently to cause the 30 lead to be condensed and separated from the zinc vapors, and to be arrested in or intercepted by the said medium before the zinc vapors can pass into the condensing area.

Because of the fact that, according to the above described practice, the refractory medium is charged directly into the retort end of the receiver itself, many disadvantages arise, due principally to the rapidity 35 with which the said medium becomes clogged by particles of coke-dust, dirt, and other impurities carried over from the retort, the clogged medium being then apt to obstruct the passage of zinc vapors to the zinc-condensing area to such a degree that, not only is the yield of purified zinc from a given charge of zinc-material appreciably diminished, but frequently such dangerous vapor-pressures are set up in the vaporizing area as 40 to result in the bursting of the retort and the total loss of the charge. Furthermore, when the medium becomes clogged and rendered 45 useless, it is impossible for the same to be

removed or disposed of without detaching the entire receiver from the retort, thus interfering with the continuity of the extracting process.

The object of the present invention is to obviate the disadvantages attendant upon the above-mentioned method of using lead-intercepting medium, and to provide means for utilizing a lead-intercepting medium which will both minimize the liability of said medium to become clogged after short usage, and also enable the same to be readily displaced or disposed of, either after its utility has become impaired, or for other reasons, without necessitating the detachment of the receiver or condenser from the retort or interfering in any way with the continuity of the zinc-extraction process. To realize this object, it is proposed to inclose and use the lead-intercepting medium in a receptacle or appliance which is separate from, or independent of, the receiver and the retort, and is adapted to be arranged in an intermediate position between the vaporizing area and the zinc-condensing area in such a manner that, while the whole of the vaporized metals from the retort are compelled to pass into or 50 through the receptacle before reaching the receiver, and are thus effectively subjected to the action of the lead-intercepting medium contained therein, the said medium is nevertheless protected or screened to a considerable degree from the coke-dust and other solid impurities in suspension in the retort vapors, and thus clogging or deterioration thereof is minimized, the period of its effective utilization is extended, and the passage 55 of the vaporized metals is not retarded until after a considerable quantity of high-purity zinc has been distilled over and collected in the receiver. Further, the receptacle is so arranged that, at any desired stage in the 60 process, it can be displaced or removed from its effective position into the retort, so as to leave a free or un-restricted passage for the vaporized metals between the vaporizing and condensing areas and admit of the extraction process proceeding uninterruptedly, although the said metal vapors that pass 65 after the displacement of the intercepting medium are no longer subjected to any special lead-intercepting influences.

The result of using the above-described

method and appliance is that after one or more tappings of high-purity spelter has been collected in the receiver by the aid of the intercepting medium in the separate receptacle, the extracting process can be continued until the charge in the retort is exhausted to obtain one or more further tappings, which yield ordinary-grade or commercial spelter.

10 In the accompanying drawings: Figure 1 is a longitudinal sectional view of a portion of a zinc extracting apparatus showing a charge of intercepting medium contained within a displaceable sleeve-like receptacle 15 carried by the inner end of the receiver and arranged so that it constitutes the only communication between the said receiver and the retort. Fig. 2 represents a cross-section of Fig. 1, taken through the retort upon 20 the dotted line 2—2, and looking towards the receiver and the separate intermediate receptacle, which is shown in end elevation; Fig. 3 represents a cross - section taken through the receiver and receptacle upon the 25 dotted line 3—3, Fig. 1; Fig. 4 represents a cross-section upon the dotted line 4—4, Fig. 1, taken through the receiver; Fig. 5 is a separate longitudinal section of the receiver; Fig. 6 is an end view thereof; Fig. 7 shows a 30 longitudinal section and two end views of the displaceable receptacle separately, and Fig. 8 represents a longitudinal section of a modified form of receptacle wherein the outlet leading into the receiver is arranged centrally of its inner wall.

The same letters of reference indicate corresponding parts in each of the several figures of the drawings.

In the accompanying drawings, I have 40 shown one embodiment of the invention wherein *a* designates the retort and *b* the receiver for the purified zinc, the latter being provided with a partially-closed inner end *b*¹, which extends into the interior of the retort 45 when the receiver is luted in position, and is provided with an opening *b*² for the reception of the sleeve-like medium-container or receptacle *c*, wherein a filling or charge *d* of anthracite coal, broken fire-brick or other suitable 50 intercepting medium, is secured by a stopping of clay *e* placed in its inner end in such a manner that an aperture or opening is left at *e*¹, above the stopping to provide for the passage therethrough of the whole of the zinc 55 vapors that are distilled over from the retort, and when it is desired to cause the intercepted and condensed lead to run back into the retort, a suitable drainage hole may be made at *a*² through the bottom of the clay stopping *e*. 60 In order to provide an effectual trap for the lead which is intercepted by the charge of medium and to prevent any of the medium from falling into the condensed metal in the receiver while still leaving a free outlet for the 65 purified zinc vapors, the forward end of the

sleeve is provided with a baffle or partition *c*¹ extending for a suitable height from its bottom edge, but leaving a top opening *c*² through which the purified vapors may issue into the receiver.

In carrying out a continuous process of obtaining one or more tappings of high-purity zinc followed by one or more tappings of ordinary grade or commercial spelter, the interception sleeve, after having been first filled 70 with the anthracite or other medium, is luted in position in the opening *b*² in the retort end of the receiver, as shown in Fig. 1, and it is so arranged that when the charge has become so contaminated with intercepted lead and 75 other matter as to be rendered useless, the said sleeve can be pushed back into the retort by the introduction of a suitable appliance through the open outer end of the receiver, thereby leaving the opening *b*² in the 80 inner end of the said receiver clear or unobstructed and permitting the subsequent passage of the vaporized metals directly from the retort to the condensing area, it being understood that the high-purity zinc is usually 85 tapped off from the receiver prior to the displacement of the sleeve and medium and that thereafter the operations are continued without the use of any lead-intercepting medium 90 to obtain the commercial grade spelter.

Fig. 8 shows a longitudinal section of a modified form of receptacle in which the outlet *c*² leading therefrom into the receiver is arranged in the middle of the inner end, instead of at the top thereof as in the previously-described form. Such a construction is found to facilitate the interception and shedding of the lead from the zinc vapors, as the solid walls above and below the said outlet constitute baffles against which the vapors impinge and are thereby made to circulate more thoroughly through the medium whereby a higher degree of purity is obtained in the zinc vapors which escape through the outlet into the receiver.

The improved method involved in the operation of a zinc-extracting apparatus embodying my invention is not claimed in the present application, such method forming the subject matter of a separate application filed 105 December 13, 1907, Serial Number 406, 391, of which the present application is a division.

I claim as my invention:

1. An apparatus adapted for use in the extraction of zinc, involving a separate 120 receptacle or carrier containing a lead-intercepting medium and adapted to be displaceably mounted between and having openings to communicate respectively with the vaporizing area and the condensing area.

2. An apparatus adapted for use in the extraction of zinc, involving a receptacle to contain a lead-intercepting medium and displaceably mounted in the apparatus between the vaporizing area and the condens- 130

ing area, the said receptacle having openings which communicate with the said areas.

3. An apparatus adapted for use in the extraction of zinc, comprising a retort, a receiver, and a receptacle or carrier to contain a lead-intercepting medium and adapted to be mounted in the retort end of the receiver, said receptacle having openings communicating respectively with the retort and receiver.

4. An apparatus adapted for use in the extraction of zinc, comprising a retort, a receiver, and a receptacle or carrier for a lead-intercepting medium formed separately from and displaceably mounted in the retort end of the receiver, said receptacle having openings for communicating respectively with the retort and receiver and is adapted to be displaced into the said retort.

5. An apparatus adapted for use in the extraction of zinc, comprising a retort, a receiver, and a receptacle or carrier for a lead-intercepting medium, adapted to be displaceably mounted within the retort end of the receiver, and provided at its end which extends into the receiver with a solid wall or baffle surmounted by an opening for the escape of the purified metallic vapors, the opposite end of the receptacle that extends into the retort having an opening for the admission of the metallic vapors from said retort.

In testimony whereof I have hereunto set my hand in presence of two subscribing witnesses.

EDWARD HENRY SHORTMAN.
